Primary Examiner — Martie K Holtje*(74) Attorney, Agent, or Firm* — Jacobson Holman, PLLC.(57) **CLAIM**

The ornamental design for a bin for aircraft storage, as shown and described.

DESCRIPTION

FIG. 1 is a front perspective view of a bin for aircraft storage showing our new design;

FIG. 2 is a partial perspective view thereof;

FIG. 3 is a front elevational view thereof;

FIG. 4 is a top plan view thereof;

FIG. 5 is a left side elevational view; the right side elevational view being a mirror image thereof; and,

FIG. 6 is a front perspective view thereof in an opened condition.

The structural elements depicted by broken lines in the drawings have been shown for the purpose of illustrating portions of the bin for aircraft storage that form no part of the claimed design.

The features depicted by broken lines in FIG. 2 have been shown for the purpose of illustrating environment that forms no part of the claimed design.
